UNITED STATES PATENT OFFICE.

WILLIAM S. PITCAIRN, OF EAST ORANGE, NEW JERSEY, ASSIGNOR TO WILLIAM S. PITCAIRN CORPORATION, OF NEW YORK, N. Y., A CORPORATION OF NEW YORK.

DESIGN FOR A COVERED DISH OR SIMILAR ARTICLE.

Application filed June 16, 1923. Serial No. 6,514. Term of patent 3½ years.

To all whom it may concern:

Be it known that I, WILLIAM S. PITCAIRN, a citizen of the United States, residing at East Orange, county of Essex, and State of New Jersey, have invented a new, original, and ornamental Design for a Covered Dish or Similar Article, of which the following is a specification, reference being had to the accompanying drawing, forming part thereof.

I claim:

The ornamental design for a covered dish or similar article as shown.

WILLIAM S. PITCAIRN.
